UNITED STATES PATENT OFFICE.

NATHANIEL H. BROWN, OF PHILADELPHIA, PENNSYLVANIA.

REVOLVING EXHIBIT-DISPLAY APPARATUS.

No. 838,075.

Specification of Letters Patent.

Patented Dec. 11, 1906.

Application filed June 28, 1906. Serial No. 323,769.

To all whom it may concern:

Be it known that I, NATHANIEL H. BROWN, a citizen of the United States, residing at the city of Philadelphia, in the county of Philadelphia and State of Pennsylvania, have invented certain new and useful Improvements in Revolving Exhibit-Display Apparatus, of which the following is a specification.

My invention relates to a revolving exhibit-display apparatus for store use in displaying changing fashions or styles and also for use as a means of advertising the same by illuminated panel means applied thereto, and in such connection my invention has relation to the constructive arrangement of the apparatus and in connection therewith of the manner of exhibiting by illuminated displays the article to attract or the information to be advertised for the benefit or advantage of the public.

My invention, stated in general terms, consists of a revolvable illuminated display apparatus constructively arranged for operation substantially in the manner hereinafter described and claimed.

The nature and scope of my present invention will be more fully understood from the accompanying drawings, as an illustration of salient features of the said invention, in which—

Figure 1 is an elevational view of a revolvable apparatus for illuminated display exhibits for advertising and other purposes embodying main features of my said invention. Fig. 2 is a vertical central sectional view of Fig. 1, showing the manner of supporting the exhibit-display device of my invention so as to be revolved, a means for illumining the opaque figured or other type of glass panels of the device from the inside thereof and the box-like base of the device above which the display device is supported, and in which base is located the actuating mechanism of the revolving device. Fig. 3 is a horizontal sectional view through the illuminated display device, and Fig. 4 is a similar view of the base of said device.

Referring to the drawings, A represents a six or more sided device having openings or panels in each side and the device made of wood or metal in skeleton form and provided with an inclined complementary sided hood a', having an opening a² in the top for a purpose to be presently explained.

B is the box-like base for supporting, by 55 means of a shaft b', journaled in the bottom and top of the same in bearings b² and b³, provided internally thereof, the said device A. The shaft b' extends into the display device A into a bearing a³ in the bottom of the device and secured thereto by means of a tightening-screw a⁴, as clearly illustrated in Fig. 2. Within the box-like base B on the shaft b' is rigidly mounted a worm-wheel c, meshing with a worm-shaft c', mounted in bearings 65 c² and c³, supported from the bottom of the box B. This shaft c' is provided with a grooved pulley c⁴, around which passes a cord c⁵, engaging a grooved wheel c⁶, securely mounted on the commutator-shaft c' of a suitable electric motor C, held in a fixed position within the base B, as clearly illustrated, for example, in Fig. 4. The starting and stopping of the motor, as will be well understood, is controlled by an ordinary knife-switch. (Not 75 shown.) To one of the sides of the base B is fixed thereto by means of brackets d and d' a vertical tube D, provided with a T-union d², extending into the base. At the upper end of the tube D by means of unions d³ the same 80 is formed into a right-angular extension d⁵, which is extended therefrom in a downward direction at d⁶ through the opening a² of the device A, from which is suspended by means of a clamp d⁷ a rod e, carrying a series of 85 adjustable brackets e' at suitable distances apart, supporting incandescent lamps e² therefrom with their line connections 5 and 6. These connections extend through the tube D and into the base B through the T- 90 union d² and connect therewith with a suitable source of electric energy, (not shown,) whereby when the current is turned on and the motor is in action by the operating of the switch controlling the same the device A will 95 be rotated, and at the same time the device A highly illuminated from the interior, which is reflected through the glass panes a of the device A, thereby exposing to view in a highly-attractive manner the advertising or 100 other matter contained on the different series of glass panes of the device.

The illumination of the device from the inside reflected through the panes thereof may be varied at pleasure—that is, on a dissolving principle or by momentary increase or decrease of the intensity of the illumination, according to the degree of rotation of

the device, as well as position of sides with respect to other sides, dependent upon the situation of the device for the obtaining of the best effects from advertising or advantage standpoints in the use thereof.

Having thus described the nature and object of my invention, what I claim as new, and desire to secure by Letters Patent, is—

1. In a display apparatus, a base, a shaft arranged within and terminating above said base, a display-cylinder having transparent panels supported by said shaft, a support connected with said base and terminating within said cylinder, light-emitting means suspended from said support within said cylinder and held stationary by the same and means arranged in said base adapted to rotate said shaft and by the same said cylinder around said light-emitting means.
2. In a display apparatus, a base, a shaft arranged within and terminating above said base, a display-cylinder having transparent

panels supported by the free end of said shaft, and having an opening at the upper end, a support connected with said base and terminating within said cylinder by passing through an opening thereof, a rod suspended from said support within said cylinder having brackets, light-emitting means carried by said brackets and held stationary by the same, a worm-wheel secured to said shaft, a worm-shaft meshing with said worm-wheel, said worm-shaft, when rotated, adapted to rotate said worm-wheel and by the same said shaft and cylinder around said light-emitting means and when stationary locking said cylinder in a given position.

In witness whereof I have hereunto set my signature in the presence of two subscribing witnesses.

NATHANIEL H. BROWN.

Witnesses:

J. WALTER DOUGLASS,
THOMAS M. SMITH.
